UNITED STATES PATENT OFFICE.

HENRY W. SCOTT, OF GREENCASTLE, PENNSYLVANIA, ASSIGNOR TO J. B. CROWELL & CO., OF SAME PLACE.

SEEDING-MACHINE.

SPECIFICATION forming part of Letters Patent No. 252,528, dated January 17, 1882.

Application filed October 5, 1881. (Model.)

To all whom it may concern:

Be it known that I, HENRY W. SCOTT, of Greencastle, county of Franklin, State of Pennsylvania, have invented new and useful Improvements in Seeding-Machines, of which the following is a full, clear, and exact description, reference being had to the accompanying drawings, making part of this specification, in which--

10 Figure 1 is a rear elevation of so much of a grain-drill as is necessary to show my improvement, and Fig. 2 represents a vertical longitudinal section through the same.

15 My invention relates to a novel arrangement of truss-bar, in connection with a transverse frame or axle-bar, whereby it is made not only to stiffen said bar and prevent its sagging under the weight of the load, but is also made to assist in relieving the spring-hoes 20 from obstructions by breaking the joint between the hoe and its draw-bar; and it consists in the employment of a truss rod or bar connected with pendent lugs on the main transverse frame or axle-bar, or on the inner ends 25 of the stub-axles connected with said bar, in connection with a support or upright intermediate between said supporting-lugs for stiffening and supporting said axle-bar midway of its length, as hereinafter explained.

30 The machine, in its organization or general arrangement and construction, may be similar to such as are now in use, and it need not therefore be described in detail, further than is necessary to explain my improvement.

35 In the accompanying drawings, A represents the main frame, which may be of the usual rectangular form, A' representing the main transverse frame-bar, to which the stub-axles B and B' are secured in any usual or 40 preferred manner; or, where desired, a stationary through-axle may be used, constituting both the frame and axle-bar.

C and C' are the main carrying and driving wheels mounted on the axles B B'.

45 Upon the inner ends of the stub-axles B B', where the latter are used, are pendent lugs or ears b b', to which the ends of a transverse truss rod or bar, D, are bolted, said bar being

thereby suspended horizontally underneath the main frame or axle-bar, as shown.

To the bar A, midway of its length, is secured a pendent bracket or support, E, which, by preference, is forked or slotted in its lower end to receive the bar D, fitting snugly therein. The support E is made of sufficient length to adapt it, when the bar D has been bolted at one end, and is forced upward into place to be bolted to its supporting-lug, to arch or spring the bar A' upward slightly at its center, as shown, and thereby relieve it from any tendency to sag under the weight of the load of grain, &c., which may be imposed upon it. By reference to Fig. 2 of the drawings it will be seen that this truss rod or bar D is arranged about in the same transverse line with or slightly in advance of the joints between the yielding or spring hoes F and the draw-bars G. This arrangement facilitates the breaking of the joint between the hoe or shoe and the draw-bar when the shoe meets with an obstruction, which would be liable to injure or break it, if it could not yield to such obstruction, as ordinarily the first effect of such obstruction will be to raise the draw-bar into contact with the truss-rod D, which serves to hold it while the shoe is being crowded backward, overcoming the tension of its retaining-spring until the shoe is in position to ride over the obstruction. The truss-rod D is thus made to serve the double purpose of stiffening the main frame or axle-bar, and of assisting in the operation of breaking the joint between the shoe and draw-bar for facilitating the passage of the hoes over obstructions. Another advantage resulting from this arrangement of the truss-rod is that it prevents the drag-bars from rising high enough in passing over an obstruction to allow the hoes to strike the lugs on the lifting-roller or the tube-board, and thus prevents injury to said parts.

Only one support E is described intermediate between the pendent lugs b b' supporting the truss-rod D, but it will be apparent that one or more additional supports may be used, where the length of the axle-bar requires it.

The hoes or teeth may be hinged to the draw-bars in any usual manner, and any usual or preferred form and arrangement of spring and retaining devices for holding said hoes in working position may be employed.

Having now described my invention, what I claim as new is—

The main frame or axle-bar provided with the suspended truss rod or bar, in combination with the draw-bars and the yielding hoes hinged thereto, arranged and operating substantially

as described, whereby the truss-rod is made not only to stiffen said frame or axle-bar, but also to facilitate the passage of the hoes over obstructions, as explained.

In testimony whereof I have hereunto set my hand this 4th day of October, A. D. 1881.

H. W. SCOTT.
